UPRIGHT SPIRAL ROLLING BALL SKILL GAME APPARATUS

Joseph J. Schigas, Erie, Pa., assignor to Louis Marx & Company, Inc., New York, N. Y., a corporation of New York

Application June 16, 1953, Serial No. 25,528

Term of patent 7 years

(Cl. D34—5)

To all whom it may concern:

Be it known that I, Joseph J. Schigas, a citizen of the United States and a resident of Erie, in the county of Erie and State of Pennsylvania, have invented a new, original, and ornamental Design for an Upright Spiral Rolling Ball Skill Game Apparatus, of which the following is a specification, reference being had to the accompanying drawing, forming a part thereof, wherein:

Fig. 1 is a front elevational view of an upright spiral rolling ball skill game apparatus, showing my new design;

Fig. 2 is a bottom plan view;

Fig. 3 is a side elevational view looking from left to right in Fig. 1, partly broken away for convenience of illustration; and

Fig. 4 is a side elevational view looking from

right to left in Fig. 1, with the uppermost end of the view broken away for convenience of illustration.

The drawing is diagonally lined to indicate transparency.

I claim:

The ornamental design for an upright spiral rolling ball skill game apparatus, substantially as shown and described.

JOSEPH J. SCHIGAS.
